UNITED STATES PATENT OFFICE

162,966

TOY CABLE CAR

Theodore Lewy, San Francisco, Calif.

Application February 9, 1949, Serial No. 763

Term of patent 7 years

(Cl. D34—15)

To all whom it may concern:

Be it known that I, Theodore Lewy, a citizen of the United States, residing at San Francisco, State of California, have invented a new, original, and ornamental Design for a Toy Cable Car, of which the following is a specification, reference being had to the accompanying drawings, forming part thereof.

Figure 1 is a perspective view of a toy cable car, showing my new design.

Figure 2 is an end elevation of the toy cable car illustrated in Figure 1.

The opposite side and opposite end of the toy cable car have substantially the same appearance as the side and end shown in Figures 1 and 2 of the drawing.

I claim:

The ornamental design for a toy cable car, substantially as shown and described.

THEODORE LEWY.
